HYDRAULIC SLIP COMPENSATING VALVE

Ernest E. Wagner, Santa Ana, Calif.

Filed July 12, 1957, Ser. No. 671,468

10 Claims. (Cl. 137—487)

This invention pertains to pumps, hydraulic motors and related equipment in hydraulic circuits in general and to means for compensating for variations in the output speed of hydraulic motors, the output volume of pumps and the volume of fluid flowing in hydraulic systems and it has particular reference to a device for compensating for said variations when caused by changes in fluid pressure (p.s.i.) which, perforce, cause proportional changes in the volume of fluid slipping past capillary clearances between moving and movable parts in the circuit which may be subjected to a pressure differential.

The object of the invention is to provide a means for offsetting the effect of hydraulic slip past the capillary seals, thereby to prevent hydraulic motors from stalling at slow speeds and variable delivery pumps from ceasing to deliver fluid when set to pump small quantities.

A further object of the invention is to provide a device by which controlled quantities of fluid may be subtracted from a fluid circuit to offset the disturbing effect of any variation in slip past the capillary seals and thereby to hold the output of hydraulic motors and pumps uniform at a reduced capacity.

A still further object of the invention is to provide a device by which metered quantities of fluid may be added to a hydraulic circuit to cancel the disturbing effect of variations in slip past the capillary seals, caused by variations in pressure, and thereby maintain the output of hydraulic motors and pumps uniform at maximum capacity.

Another object of the invention is to provide a metering instrument capable of automatically metering fluid in or out of a hydraulic circuit or system in such proportions that the rate of operation of hydraulic motors and pumps in the system will not fluctuate under load changes ranging from no load to full load.

An additional object of the invention is to provide a device of the character referred to in which the rate of flow for a given pressure may be readily varied.

These and other objects are accomplished by a form of device shown, in preferred form, in the accompanying drawings, in which:

Fig. 1 is a longitudinal section through the valve on line 1—1 of Fig. 2.

Fig. 2 is a cross section on line 2—2 of Fig. 1.

Fig. 3 is a section on line 3—3 of Fig. 2, showing the vertical disposition of the various openings and passageways.

Fig. 4 is a partial cross section on line, 4—4 of Fig. 1, showing the position of the various passageways relative to one another after removal of the center rod and differential plunger.

Fig. 5 is an enlarged fragmentary cross section through the capacity control device, which is shown with its channels in a position of minimum capacity.

Fig. 6 is an enlarged fragmentary cross section, similar to Fig. 5, showing the channels in a position of maximum capacity.

Fig. 7 is a schematic representation of Fig. 1 without the center rod.

Fig. 8 is a circuit diagram showing a slip compensating valve and a hydraulic motor in parallel and their respective pressure vs. slip diagrams.

Fig. 9 is a schematic representation of the passageways of a slip compensating valve for bleed-out service.

Throughout the drawings, similar reference numerals designate similar parts.

10 The symbols PL , P_o and P_c , alone and in combination, are used in the drawings and specification to facilitate a clear understanding of the instrumentality and its operation. They denote the following:

15 PL , the pressure registered in p.s.i. gauge on the high pressure side of a pump or hydraulic motor under load.

PL max., the maximum operating pressure for which the valve is designed.

20 P_o , the pressure registered in p.s.i. gauge on the low pressure side of a unit.

$PL - P_o$, the pressure differential representing the working load on the system.

25 P_c , the control pressure in p.s.i. generated by the hydraulic slip compensator in response to the pressure differential $PL - P_o$. P_c , is a gauge pressure only for P_o gauge=zero.

VSC, hydraulic slip-compensating valve.

The construction of the valve is identical for both bleed-in circuits—circuits to which a controlled quantity of fluid is added—and bleed-out circuits—circuits from which 30 a controlled quantity of fluid is subtracted—and, provided the valve, in all its parts, is designed to withstand the maximum pressure likely to occur, it may be employed for either service. The description will, therefore, be limited to the use of the valve for bleed-out service and, furthermore, it will be limited to a valve for holding the speed of a hydraulic motor at constant r.p.m., though subject to the disturbing influence of a varying load (torque), for the reason that the same valve will perform equally well when used for holding constant, the rate of flow of a pump, though subject to the disturbing influence of a varying load (p.s.i.).

35 Reference is made to Fig. 1, wherein is shown a valve comprised of 3 pieces or sections, 11a, 11b, and 11c, which are joined together by bolts 12 and 12a substantially as shown in Figs. 1 to 4, to form a valve body having covers 15, 16 at the respective ends thereof, said covers being secured in position by said bolts 12, 12a.

40 A housing 13 is bolted to the center section 11b of the valve body. Said housing 13 is provided with a bore 86 in which is disposed a pressure control valve spool 85 that is adapted for operation relative to an inlet port 40 and an outlet port 42 in said bore. Both ends of the bore 86 are closed respectively by plugs 90 and 91, which thread into the housing 13 and are sealed by O rings 92 and 93 respectively. Each plug 90 and 91 is provided 45 with a piston 94 and 95 which bears against the respective ends of and are adapted to actuate said valve spool 85. Said plugs 90 and 91 are provided with fluid inlet-outlet passages 96 and 97 respectively.

45 The housing 13 is provided with a threaded inlet passageway 17, Fig. 1, which communicates, via passageway 93 in the center section 11b, with coaxial, longitudinal passageways 18b, 18a and 18c, which form a continuous passageway throughout the valve body and through which fluid is conducted from the inlet 17 to the caps or covers 50 15, 16 which, in turn, are in communication with differential plunger sections 21 and 23 respectively. Passageway 18b also communicates via passageway 41 with the port 40, heretofore referred to.

55 The valve body sections 11a and 11c are provided with concentric differential bores 19 and 20 respectively—the latter bore being the smaller—for guiding a differ-

ential plunger composed of integrated sections or members 21, 22, 23, preferably threadedly connected together. Reference to a differential plunger, hereinafter, shall be understood to refer to the integrated structure consisting of sections 21—22—23.

Section 21 of the differential plunger is a smooth surfaced, tubular member having a close sliding fit in bore 19. It is threaded internally at one end to receive an externally threaded end 103 of the center section 22 which has a hole 100 extending centrally throughout its length and which is provided, at each end, with internal threads 101, 102.

Upon a portion of the periphery of section 22 are formed serrations 49 that cover the entire circumference and are adapted to mate with serrations 48 concentrically arranged within the center section 11b of the valve body. Figs. 5, 6.

The upper internal thread 101 in the center section 22 receives a fitting 64, threaded externally on both ends, one end to fit thread 101 and the other end to thread into one end of an extension spring 89, concentrically disposed within the hollow member 21 of the differential plunger, thereby to connect the differential plunger and spring together.

The extension spring 89, at its opposite end, is in turn threaded onto a calibrator fitting 62 suspended from an antifriction bearing 63 mounted in a threaded sleeve 65, adjustable axially within the valve body section 11a, so that the differential plunger, after the spring is calibrated, can be raised or lowered relative to the channels between the serrations 48 in the valve member 11b.

The lower internal thread 102 of section 22 receives the external, mating thread of the plunger head, section 23. The circumference of the piston like section 23 forms a sliding capillary seal with the bore 20. A hole 105 extends through section 23 concentric with its axis and forms a sliding capillary seal with a central member 24. The fitting 64 in the upper end of section 22 also has a hole 104 through it, concentric with the axis of the differential plunger and it also forms a sliding capillary seal with the central member 24 and thus provides an annular space 37 within the center section 22, which is defined by the central member 24 the hole 100 and the two capillary end seals 104 and 105.

The central member 24, Fig. 1, extends from a point near the bottom cover 16, through the differential plunger to a point beyond the capillary seal 104, as shown, and near the bottom thereof is provided with a control pressure port 99 which is connected to the aforementioned spool actuating piston 95 by passageways 25 in said central member 24, passageway 26 within a tube 31 disposed in a clearance hole 106 in an end of the central member, passageway 27 in the cover 16, Figs. 1, 2, 4, passageways 28c and 28b in the body sections 11c and 11b, passageway 29 in 11b, Fig. 2, passageway 30 in block 13 and passageway 97, heretofore referred to, in the plug 91. Said spool actuating piston 95 is adapted to operate the pressure control valve spool 85 in a manner, as herein-after described.

A housing 14 is provided with a threaded outlet 32 for connection with the low pressure side of a hydraulic system in which the valve is to operate. Outlet 32 communicates outlet pressure P_o , via passageways 33 in the housing and 34 in the valve body, to a chamber 35 within the valve body section 11b. The chamber 35 is in communication with the annular space 37 via passageways 36 passing through the walls of sections 21 and 22 of the differential plunger. As the central member 24 is of equal diameter throughout, pressure in the annular space 37 has no effect upon the action of the differential plunger, but the outlet pressure P_o is brought to bear upon surface 38, which is the inner end of the plunger head 23, for reasons presently explained.

Particular attention is drawn to the following in connection with the forces operating to automatically meter

controlled amounts of fluid: The effective differential action on the differential plunger is proportional to the product of the difference in the areas of the plunger sections 21 and 23 and the pressure differential $PL-P_o$.

5 The pressure PL acts externally on the differential plunger from opposed ends, Fig. 7. The pressure P_o acts within the chamber 35 opposing entrance of the plunger 19 into the chamber. The pressure P_o acts within an annular space or chamber 46, provided in the end of the center section 11b, therefore the area of section 23 and section 22 must be equal to avoid imbalance under the influence of the control pressure P_c .

10 The area of the serrated or channeled outline 49 of the plunger section 22, Fig. 6, can be reduced to an equivalent area of smooth diameter. For serrations having an outline corresponding to that of conventional gear teeth the equivalent smooth diameter is slightly larger than the pitch diameter but smaller than the O.D.; it lies between the two. In Fig. 7, 49a represents the

15 equivalent smooth diameter of the channels or teeth 49 of section 22. The equivalent smooth diameter 48a of the internal teeth 48 must, perforce, be equal to the equivalent smooth diameter 49a of its mating external teeth. Plunger diameter, section 23, has been made

20 equal to the equivalent smooth diameter 49a, therefore, the areas on both sides of the chamber 46 having been made equal no disturbing action by the control pressure P_c is possible, furthermore, the diameter 49a in the chamber 35 being the equivalent of the diameter of the channels or teeth 49, section 22, the effective differential action of the differential plunger assembly 21—22—23 is preserved. It has also been shown, hereinbefore, that the pressure P_o in the annular space 37 is fully balanced, therefore, Fig. 7, is in principle, the equivalent arrangement of Fig. 1 in respect to the forces acting upon the differential plunger.

25 With the aid of Fig. 7, the forces acting on the differential plunger are plainly evident. The area of section 21 minus section 23 or the equivalent area thereof, namely section 22 in the chamber 35, is under the influence of the net pressure of $PL-P_o$. The two-area times p.s.i.—produce a force which is opposed by the tension of the extension spring 89. With an increase in $PL-P_o$ the differential plunger moves downwardly, with

30 reference to Fig. 7, until the increasing tension in the spring restores a balance and vice versa. Considering the foregoing and the characteristics of springs, it is evident that movement of the differential plunger is proportional to the net pressure $PL-P_o$.

35 The capillary seal 105—defined by the hole 105 in the plunger head, section 23, the central member 24 and the distance between the ends 38 and 39 of section 23—is an integral part of the differential plunger and therefore traverses upon the stationary central member 24 in varying amounts proportional to the pressure differential $PL-P_o$.

40 Port 99 in the rod 24 is so positioned that the surface 39 coincides with the edge of the port 99, as shown, whenever $PL-P_o$ equals zero. The spring 89 is so proportioned that the position of surface 38 opposing surface 39 of the seal 105 coincides with the opposite edge of the port 99, whenever $PL-P_o$ equals the maximum pressure PL_{max} for which the valve is designed.

45 Whenever the capillary seal 105 moves along the member 24, the port 99—being stationary—is spaced varying distances, proportional to $PL-P_o$, from the shoulders 38 and 39. As there also is a proportional pressure drop along the viscous flow space 105 between the shoulders, independent of the location of the port 99—

50 from a max. pressure PL at point 39, to a min. pressure P_o at point 38—there is a continuously varying control pressure P_c with varying $PL-P_o$. For an outlet pressure P_o equal to zero gage the control pressure P_c will vary from zero, for $PL-P_o$ equal to zero, to a maximum equal to 25% of PL_{max} for $PL-P_o$ equal to

55

PL max./2, after which it again returns to P_c equal to zero for $PL - Po$ equal to PL max.

Bleed-off or bleed out fluid may flow from the inlet port 40 around the neck of the valve spool 85 to the outlet port 42, thence via passageways 43, 44 and 45 to the chamber 46 in the center section 11b of the valve body. From chamber 46 the fluid flows with negligible resistance through an annular space formed by a neck 47 in section 22 and the internal channels formed by the teeth 48 in the valve body, section 11b, until it encounters viscous flow passageways 50, Figs. 5 and 6, formed between the internal channels or teeth 48 provided in the valve body and the external channels or teeth 49 provided on the differential plunger section 22, the two sets of teeth telescoping varying amounts and thereby varying the length of the viscous flow passageways proportional to the pressure differential $PL - Po$ for reasons appearing later.

The pressure in the chamber 46 must at all times be equal to the control pressure P_c in the port 99 of the central member 24, irrespective of the volume of fluid the valve is called upon to meter out. For the purpose of checking upon the pressure in the chamber 46 so as to maintain the required control pressure P_c in accordance with the requirements dictated by the pressure differential $PL - Po$, pressure in the chamber 46 is conducted via passageways 51, 52 and 53 in the valve section 11b, Fig. 2, passageway 54 in the valve block 13 and passageway 96, in the plug 90, to the spool actuating piston 94, thereby, to actuate the pressure control valve spool 85 as hereinafter described.

Seepage from the spool 85 and the pistons 94, 95 is collected in the end spaces 54, 55 of the spool bore 86 and carried from there to the low pressure side of the system via dual passageways 56, 57 in the housing 13 and passageways 58, 59, 60 in the surface thereof, as shown in Figs. 2 and 4. Passageway 61 in section 11b of the valve body carries the seepage fluid from passageway 60 to the chamber 35, in turn, communicating with the outlet 32 in the housing 14 via passageways 34 and 33.

A variation in the capacity of the valve may be achieved by varying the distribution of the clearances between opposite sides of the serrations or teeth 49, and means for accomplishing this include a toothed lever 73, pivoted at 74 in the housing 14, which is inserted into the center member 11b through an opening 75, until the tooth 76 on the end of the lever is in mesh with the gear teeth 49. Lever 73, on the end opposite the tooth, is machined spherically as shown at 88. The spherical surface 88 rides upon the internal surface of a conical bore 77, machined in the end of a regulating screw 78, which is provided with a seal in the form of an O ring 79 and a hexagon socket 80 in its outer end by which the regulating screw can be moved in or out and thereby swing the toothed lever 73 upon its pivot 74, which action moves the external teeth 49 on the plunger section 22, circumferentially and relative to the internal teeth 48 in the body member 11b thereby varying the spaces between said teeth, which spaces actually are viscous flow channels and hence the capacity of the valve. This arrangement in no way interferes with the required axial movement of the differential plunger.

Without describing the functioning of the capacity control until later but assuming the setting to be as shown in Fig. 5, which is the position of minimum capacity, a position in which the teeth are so aligned that the clearance between them is equally divided—one-half on one side and one-half on the other side of each tooth—it will be found that the rate of flow through the valve is controlled as a function of $PL - Po$, that operation is fully automatic and attained in the following manner:

A torque load imposed on the output shaft of a hydraulic motor will result in an increase in $PL - Po$ in the hydraulic system which increase is communicated to

opposite ends of the differential plunger and forces it to move until a balance is re-established between the hydraulic force and the opposing force of the extension spring 89, as hereinbefore described.

Movement of the differential plunger changes the control pressure P_c in the port 99 of the central member 24. A change in P_c is communicated to the pressure control valve 85 in housing 13, there to act on the spool actuating piston 95. Opposed to piston 95 is the piston 94 in communication with chamber 46 by passageways previously described. The direction in which the valve spool 85 will move depends upon which piston, 94 or 95 exerts the greater force.

In this connection, attention is again drawn to several important functional relationships of the valve, namely: The manner in which P_c varies; increasing first, then decreasing as $PL - Po$ continues to increase. For bleed-out service the length of the viscous passageways 50 increases proportional to the increase in $PL - Po$, while the volume of fluid Q_{Bo} metered out decreases inversely proportional to $PL - Po$. The operating pressure PL minus the control pressure P_c , that is $PL - P_c$, represents the pressure across the orifice of the inlet port 40 of the pressure control valve. For an increasing load on the unit there is a proportional increase in the operating pressure PL , which, however, increases at a faster rate than the control pressure P_c ; therefore $PL - P_c$ increases more and more rapidly as PL increases. The net result is that for bleed-out service the orifice area of the control valve, between spool 85 and port 40, must be progressively reduced by smaller and smaller increments for an increasing $PL - Po$ and vice versa. The interaction of these variables is more readily visualized by expressing the relationships algebraically. It can be shown that:

$$Q_{Bo} = \frac{P_c K}{L v}$$

Q_{Bo} = Volume of fluid metered out by the slip compensator proportional to PL max. — PL .

$L v$ = Length of viscous flow channels or passageways 50, proportional to $PL - Po$.

LV max. = Max. length of LV for $PL - Po = PL$ max.

K = A constant based on the proportions of the cross section of the viscous flow channels 50.

$$P_c = PL \left(1 - \frac{PL}{PL \text{ max.}} \right); LV = PL \frac{L v \text{ max.}}{PL \text{ max.}}$$

By inserting the above last two values in the first formula, the rate of flow is shown to be:

$$Q_{Bo} = (PL \text{ max.} - PL) \frac{K}{L v \text{ max.}}$$

The last expression shows that the volume Q_{Bo} flowing is inversely proportional to the load PL , a prerequisite for bleed-out service. $L v$ max. is fixed. Changing K (channel cross section) changes Q_{Bo} , the volume metered out for a given pressure.

The correct value of the control pressure P_c is generated in the valve in the port 99, likewise, the correct value for the channel length $L v$ by the telescoping action of the channels 48 and 49, and both values have been shown to be proportional to $PL - Po$. P_c and $L v$ are continuously combined in the chamber 46 and its extension with the internal teeth 48, with the result, that the correct control pressure acts on the correct length of channel or passageway, which has been given a cross section dimensionally proportioned so as to be numerically equal to K and thereby automatically meter out the correct volume of fluid for a given pressure differential $PL - Po$.

From the foregoing it is evident that a change in cross section of the flow channels 50 will change K and thereby alter the volume rate of flow for a given pressure without altering the characteristics of the valve in any

other respect. The positions of the teeth for maximum and for minimum flow are shown in Figs. 6 and 5 respectively. The ratio of maximum flow to minimum flow is 4:1, since fluid flow in capillary channels of rectangular form is proportional to the cube of the depth of the channel.

Fluid conducting passageways in the valve are indicated diagrammatically in Fig. 9. Passageways intended to transmit pressure primarily, extend from the port 99 via cover 16 to the plunger 95 and from the chamber 46 to the plunger 94.

Fluid enters the valve from the system at 17 under the influence of $PL - Po$ and flows to and exerts pressure upon the differential plunger sections 21 and 23. At the same time fluid flows to the pressure control valve spool 85, in varying amounts, as demanded by $PL - Po$. An increase in pressure in the system causes the differential plunger to move down—bore 19 being larger than bore 20—therefore, fluid is taken into bore 19, discharged from bore 20 up the passageways 18a, b, c to the bore 19 which, however, requires more fluid than is discharged from 20, consequently some fluid will have to be taken in from the system, a relatively small amount only being needed, as the two bores have only a small difference in diameter.

The fluid flowing continuously to the spool 85 is conducted from port 40, via port 42, to the annular space 46, thence through the flow regulating passageways 50, formed by the teeth 48 and 49, Figs. 5, 6, to the chamber 35 and from there to the outlet 32 to return to the system.

Under the influence of the working pressure PL in the bore 20 and the outlet pressure Po in the annular space 37, viscous flow takes place between the central member 24 and the capillary seal 105, thereby generating the correct control pressure in the port 99, which is transmitted to the piston 95. Fluid flow from the port 99, Fig. 1, to the piston 95, Fig. 2, must be kept as close to zero as possible, to preclude the possibility of generating a distorted value for the control pressure.

Another pressure transmitting line brings the pressure in the annular space 46 to bear upon the piston 94. Fluid flow in this line must also be kept to a minimum to limit pressure drop.

Referring to Figs. 1 and 2, and assuming that the valve is operating, e.g., under a torque load represented by $PL - Po = 100$ p.s.i. and that the valve spool 85 and the differential plunger are correctly positioned for such a load, then, upon encountering an increased load, the system will react by an increase in $PL - Po$ as evidenced by an increase in PL at the inlet connection 17, which forces the differential plunger down, with the result outlined above. Acceleration and displacement of the differential plunger requires time, not much, however enough to result in a perceptible lag between the arrival of the full increase in Pc beneath the spool actuating piston 95 and an increase in PL in the port 40, the latter, for all practical purposes, takes place instantaneously. The increase in PL in the port 40 is transferred to the chamber 46 and from there to the spool actuating piston 94. Build-up of pressure between the two points 40 and 94 is somewhat cushioned by the flow of fluid being metered out via the viscous passageways 50. This latter action is to a good extent offset by the downward movement of the differential plunger and the consequent increase in resistance of the passageways 50 due to telescoping, which action, of its own accord tends to raise the pressure in the chamber 46. Since the increased load on the system results, first, in an increase in the force exerted by the piston 94 over that of piston 95, the valve spool 85 will move to close the port 40 somewhat and thereby reduce the pressure in the chamber 46 and beneath the piston 94 until balance is reestablished. If the valve reduces the flow through the port 40 to less than that required to hold the pressure in the

chamber 46 to the proper value against the fluid being metered out, then, the pressure in the chamber 46 and against the piston 94 will drop. As soon as the force on piston 94 is less than that on piston 95, the pressure of the latter being controlled independently by $PL - Po$, as hereinbefore explained in detail, the valve spool 85 will be forced to open somewhat until a balance between the two pistons is attained and the pressure in chamber 46 corresponds to that in the control pressure port 99. Operation is therefore fully automatic and in direct response to load changes on the system.

The immediately foregoing description pertains to the operation of the valve upon encountering a load increase. A decrease in the load on the system is reflected by a decrease in PL at the inlet to the valve, in response to which the valve increases the volume of fluid flowing through it. In response to the pressure change the valve spool 85 must open progressively greater and greater amounts as the pressure continues to decrease. The sequence of events is such that the pressure in the chamber 46 will drop first, reducing the force of the piston 94 below that of the piston 95 and thereby opening the valve spool 85 until the pressure again balances, substantially the same as for an increase in pressure, except in reverse order.

A fact, generally overlooked, is that speed variation in a hydraulic motor, with load changes, is unavoidable and occurs irrespective of all provisions made to hold the volume of fluid delivered to the unit at a constant rate. The use of standard flow valves, pressure compensated, is accepted practice but they cannot fully compensate for speed fluctuations with load changes.

It is readily apparent that any change in the volume of the fluid flowing to a unit will cause a corresponding change in the output speed of any hydraulic motor in the circuit. What is not so apparent is the fact that for a constant flow of oil to a unit, irrespective of the means by which it is kept constant, there is still a variation in speed with a change in load and that this variation is due to internal slip. In a circuit of the type supplied with a constant volume of fluid by means of a pressure compensated flow control valve, the addition of a slip compensator in parallel with the hydraulic motor will result in a constant speed output for any load from no load, to full load, as presently explained:

In the foregoing the operation of and the means by which the valve is caused to function automatically has been outlined and it has been shown that the output of the valve is opposite to the normal output of capillary passageways under hydraulic pressure namely: Fluid flow through the valve decreases proportionally to an increase in pressure, whereas, the normal course of action is for the flow to increase proportionally to pressure. The output of the valve is therefore inversely proportional to that of normal capillary action. The design and the characteristics of the valve are dictated by the requirements of the method employed to compensate for speed variations which are due to hydraulic slip, which is an inherent characteristic of hydraulic equipment of the type wherein fluid under pressure is restrained from free flow by capillary clearances between moving or movable parts.

In a positive displacement hydraulic motor, flow through capillary clearances under pressure results in a volume of fluid slipping through the clearances which is known as the slip volume Qs or slip and which is proportional to PL . See Fig. 8. Dividing the slip volume in cubic inches per minute by the displacement per revolution of the rotor in cubic inches results in a figure expressing the slip in r.p.m. Obviously, as PL increases so will the slip r.p.m. and, providing fluid flow to the unit is constant, the output speed must decrease a like amount.

In the hydraulic slip compensator the volume Qb metered out is inversely proportional to PL , see Fig. 8, and therefore proportional to PL max.— PL , consequently,

for an increase in PL there is a proportional decrease in the volume Q_{Bo} metered out.

Fig. 8, applies alike to circuits including a hydraulic motor or a pump. For a hydraulic circuit, embodying a hydraulic motor, fluid flow through the motor coincides with the direction of the arrows marked M . Flow through the slip compensating valve can only be from PL to Po (from high to low pressure). The function of the equipment being compensated is immaterial, metering is always inversely proportional to pressure.

Assuming, as an illustration, that a hydraulic motor is operating in a circuit in which a constant rate of fluid flow is continuously maintained irrespective of pressure fluctuations, then the hydraulic motor will run at a constant speed only as long as there is no pressure change. When the hydraulic motor encounters resistance an increase in pressure in the system will result which will have no effect on the total volume of fluid flowing—since it was stipulated that the volume flowing is to remain constant irrespective of pressure changes—but the slip r.p.m. of the hydraulic motor will increase and therefore the speed of the unit decrease.

By placing a hydraulic slip compensator in such a circuit, in parallel with the hydraulic motor, the equivalent of additional slip is added to the circuit by the valve, see slip diagrams, Fig. 8. The differential pressure $PL - Po$ is the same in both legs of the circuit, therefore, a given pressure PL will result in a total slip volume amounting to the motor slip volume Q_s , plus the bleed out volume Q_{Bo} , the sum of which is equal to Q_s max. From Fig. 8 it is evident that Q_s plus Q_{Bo} always equals Q_s max. irrespective of the pressure. Q_s max. is a constant for the system. By converting the slip volume Q_s max. to slip r.p.m. and subtracting the so derived slip r.p.m. from the theoretical r.p.m., the true output r.p.m. for the motor is obtained. Particular attention is called to the fact that a variation in pressure no longer causes the slip r.p.m. of the motor to vary. The unit runs at a slightly reduced speed, that is, somewhat slower than the maximum theoretical value, but it runs continuously at a constant output speed, irrespective of pressure variations.

Response to a change in the volume of fluid sent to the hydraulic motor, whether an increase or a decrease, is immediately reflected in a proportional increase or decrease in r.p.m. and speed changes due to changing torque loads are automatically cancelled. Hydraulic motors are also prevented from stalling at extremely slow speeds, due to sudden load changes. Likewise variable delivery pumps will not stall, that is, fail to deliver fluid against an increasing discharge pressure when they are set to deliver small quantities of fluid, as explained below.

In the opening statement it was pointed out that the same valve, without regard to pressure variations, may be used for holding the speed of a hydraulic motor constant as well as for holding the rate of flow of a pump constant. Not only are the details of construction and operation identical for both services, but in the majority of the cases which incorporate a pump and a motor in a common hydraulic circuit, a single valve will control both units.

Assuming, as an illustration, that a pump is operating in a hydraulic system in which the speed of the pump is kept constant, regardless of load fluctuations, then the pump will deliver fluid at a constant rate as long as there is no change in pressure. Whenever the fluid delivered by the pump encounters more resistance the pressure in the system will increase. This will have no effect on the speed of the pump—since it was stipulated that the speed is kept constant irrespective of load changes—but the hydraulic slip of the pump will increase proportionally to the increase in pressure and therefore the net delivery decrease in proportion.

The slip r.p.m. is as useful a concept in connection with a pump as it is in connection with a hydraulic motor. Applied to a pump the slip r.p.m. represent a

loss in delivery equivalent to the loss of an equal number of r.p.m. Numerically the volume lost will equal the slip r.p.m. times the actual displacement of the rotor in cubic inches per revolution.

5 If a pump and a motor are alike in all essential dimensions, then the slip r.p.m. will also be the same, therefore, the reduction due to slip, in the output speed of a transmission consisting of the two, will be 2 times the slip r.p.m. The pump will fall short of its theoretical delivery by an amount equivalent to the slip r.p.m. The motor cannot turn out r.p.m. for fluid it did not receive, so it will show a shortage equal to the slip r.p.m. it did not receive plus its own slip r.p.m. In other words, a loss equal to the sum of the slip r.p.m. of both units.

10 By placing a hydraulic slip compensating valve in a hydraulic circuit in parallel with a pump, the equivalent of additional slip is added to the circuit by the valve, see slip diagrams, Fig. 8. For a system incorporating a pump fluid flow through the system coincides with the arrows marked P . The pump in forcing fluid to flow in the direction of the arrows P raises the pressure in the system from Po to PL , but the bleed-out volume Q_{Bo} , that is, the volume metered-out of the system can only flow from PL to Po (from high to low pressure) through the valve.

20 The differential pressure $PL - Po$ is the same in both legs of Fig. 8, therefore, a given pressure PL will result in a total slip volume equal to the pump slip volume Q_s , plus the bleed-out volume Q_{Bo} . The sum of the two is equal to Q_s max. From Fig. 8 it is evident that Q_s plus Q_{Bo} always equals Q_s max. irrespective of the pressure. Q_s max. as previously pointed out is a constant for the system. By converting the slip volume Q_s max. to slip r.p.m. and subtracting the so derived slip r.p.m. from the 30 actual pump r.p.m., the effective speed of the pump in r.p.m. is obtained.

25 Particular attention is called to the fact that a variation in pressure no longer causes the flow rate to vary. The unit delivers a slightly reduced volume of fluid, that is, somewhat less than the max. possible, but the fluid delivered is at a constant rate of flow, irrespective of pressure variations.

30 Response to a change of stroke in a variable delivery pump is immediately reflected in a proportional increase or decrease in the rate of flow and changes in the flow rate due to changing loads are automatically cancelled.

35 Because the demands of hydraulic slip no longer draw on the volume being delivered to the system, but on the volume by-passed by the slip compensating valve, the 40 danger of stalling, that is, the danger of ceasing to pump no longer exists in the event sudden pressure increases occur as a variable delivery pump approaches zero delivery.

45 In commercial practice the slip volume of a hydraulic motor can readily be held to 3% at 1000 p.s.i. under 50 which conditions the additional loss due to the slip compensator is only 3/4 of 1% with respect to full load.

The member 24 is so arranged that it can float radially without binding the reciprocating differential plunger and 55 can expand, without binding, between the covers 15, 16. A hole 66 in the spring calibrator 62 allows a pin 67 to pass through it with ample radial clearance. The pin 67 at one end bears against the cover 15 while the other end is slidably inserted in a hole 87 in the upper end—with 60 reference to Fig. 1—of the central member 24. The hole 87 also contains a spring 68 which bears against the pin and holds it against the cover 15 while bearing against the bottom of the hole 87 to hold the port 99 in the central member at all times in relative alignment with the 65 plunger head 23 by means of the thin walled, and therefore springy tube 31, without causing the central member 24 to bind in the sliding head 23. To assure proper alignment between the port 99 and the plunger head 23 a washer 69 is ground to the proper thickness while assembling the unit. Bushing 70 is brazed to the tube 31

and provided with an O ring 71 to prevent leakage from bore 20 to the hole 72.

Backlash must be eliminated to be sure that the capacity once set, does not fluctuate but remains constant regardless of disturbances and despite the fact that a definite clearance must be maintained between the teeth 48-49 in order to provide variable viscous flow passageways 50 between them. Another source of backlash and variable clearance is the sliding fit between the plunger heads 21-23 and the bores 19-20. The seepage past a plunger with full eccentricity—that is, when the O.D. of the plunger and the I.D. of its bore are in contact—is 2.5 times as great as the seepage past one that has zero eccentricity, that is, one that is fully centered. If the plunger can move around at random, in its clearance space in the bore, seepage will be erratic and cannot be compensated for.

By applying torque to the differential plunger it will attempt to rotate within its guiding bores 19-20. If it cannot so rotate, the torque applied will cause the entire assembly to pivot about the point of restraint until the clearance in the bores is taken up and the assembly is in contact with the bores along a line parallel to the axis.

Leakage will increase somewhat over the irreducible minimum but the advantage gained is that it will not be erratic but very nearly constant and therefore readily compensate for. Wear will also have little influence on the constancy of any leakage.

To eliminate backlash and variable clearances in the valve under consideration, a carefully measured clockwise torque, see arrow in Fig. 2, is applied to the spring calibrator 62, which is free to rotate on antifriction bearing 63. The torque is applied by means of a spring 84 and transferred through the extension spring 89 and the fitting 64 to the center section 22 of the differential plunger, causing one of its teeth 49 to strike the tooth 76 of the lever 73 and by reaction force the differential plunger assembly in contact with the bores 19 and 20 at a point coinciding approximately with the arrow 81 of Fig. 2, and thus hold the assembly from drifting about in its clearance space.

To further eliminate play and backlash, a spring 82 holds the lever 73 in firm rattle proof engagement with the adjusting screw 78 and a spring 83 eliminates play both in the threads of the adjusting screw 78 and the pivot 74.

What I claim is:

1. A hydraulic slip compensating valve having an inlet for fluid of variable pressure and an outlet for fluid of variable pressure and means responsive to the pressure differential between said inlet and outlet, said means comprising: a valve body having a channeled portion in a part thereof, a housing at one side of said body incorporating said inlet and having an inlet port, a regulating valve in said housing, a hydraulically actuated spring loaded differential plunger within said valve body having channels on a portion thereof adapted to cooperate with the channeled portion of said valve body to provide viscous flow passageways and regulate the length thereof proportional to said pressure differential, an inlet chamber surrounding the intake ends of said variable length passageways; an axially disposed member extending through said differential plunger, spaced capillary seals in said differential plunger defining an annular space in communication with said outlet, said axial member having an annular port adapted to cooperate with one of said capillary seals and thereby generate a variable control pressure under the action of said pressure differential applied across the ends of said seal; passageways for communicating the control pressure in said annular port to one end of said pressure regulating valve, passageways connecting the other end of said regulating valve to said inlet chamber; said inlet in said housing communicating with opposing ends of said differential plunger, said pressure regulating valve and with the inlet port to said

regulating valve in said housing, an outlet port in said housing and a passageway communicating with said inlet chamber, the ends opposite the intake ends of said variable passageways terminating in an outlet chamber, means connecting said outlet chamber with said annular space thereby communicating the outlet pressure thereto, and a housing at the other side of said valve body incorporating said outlet, said outlet chamber being connected to said outlet.

2. A hydraulic slip compensating valve having an inlet for fluid of variable pressure and an outlet for fluid of variable pressure and means responsive to the pressure differential between said inlet and outlet, said means comprising a valve body having a channeled portion in a part thereof and an inlet chamber and an outlet chamber, a hydraulically actuated spring loaded differential plunger within said valve body and channels on a portion thereof adapted to co-operate with the channeled portion of said valve body to provide viscous flow passageways and regulate the length thereof, a stationary member disposed centrally of said differential plunger and provided with an annular port, said differential plunger at both ends thereof forming a capillary seal with said central member and in the region of said annular port adapted to generate a variable control pressure under the action of said pressure differential; a pressure regulating valve, passageways for communicating the control pressure from said annular port to one end of said pressure regulating valve, passageways connecting said other end of said regulating valve with the inlet chamber of said variable length passageways; said regulating valve having an inlet port and an outlet port, said inlet communicating with the ends of said differential plunger and with said inlet port, and a passageway connecting said outlet port with the inlet chamber of said variable length passageways, the opposite end of said variable passageways communicating with said outlet.

3. A valve of the character referred to having an inlet for fluid of variable pressure and an outlet for fluid of variable pressure and means responsive, to the pressure differential between said inlet and outlet, said valve comprising a valve body incorporating said outlet and a housing incorporating said inlet, a differential plunger within and co-operating with said valve body to provide viscous flow channels, said plunger being in communication with said inlet and outlet and hydraulically actuated to regulate the volume of viscous flow; a stationary member extending through said plunger and provided with an annular port, said plunger forming capillary seals with said member for generating a variable control pressure under the action of said pressure differential; a pressure regulating valve in said housing, passageways for communicating the control pressure to one end of said regulating valve; passageways connecting the other end of said regulating valve with the inlet side of said viscous flow channels; said housing having an inlet port and an outlet port adapted to be controlled by the movement of said pressure regulating valve, a passageway connecting the inlet in said housing with said inlet port; and a passageway connecting said outlet port with the inlet end of said channels, the opposite ends of said channels communicating with the outlet from said valve body.

4. A valve of the character referred to comprising a valve body having a channeled portion in a part thereof and an outlet for fluid of variable pressure; a housing provided with an inlet for fluid of variable pressure; a differential plunger within said valve body having channels on a portion thereof for co-operation with the channels in said body to regulate the length thereof and provide viscous flow passageways therethrough, said housing having an inlet port communicating with said inlet and an outlet port, said inlet communicating with the ends of said differential plunger to actuate the same hydraulically and control the length of the viscous flow passageways, a stationary member within said differen-

tial plunger forming spaced capillary seals therewith, and having an annular port, and in the region of said port adapted to generate a variable control pressure under the action of the pressure differential between said inlet and outlet, said housing having a passageway connecting said outlet port with the inlet side of said channels, a pressure-regulating valve operable relative to said ports, means connecting said annular port to one end of said pressure regulating valve, and means connecting the other end of said regulating valve with the inlet side of said variable length channels, the outlet ends of said channels communicating with said outlet.

5. A valve of the character referred to, comprising a valve body having an inlet for fluid of variable pressure and an outlet for fluid of variable pressure, a differential plunger in said valve body responsive to the pressure differential between said inlet and outlet and in communication at the top and bottom thereof with said inlet, said plunger having means for co-operation with said body to provide variable length viscous flow passageways and being hydraulically actuatable to regulate the rate of flow through said passageways, a stationary member extending through said plunger and provided with an annular port adapted to generate a variable control pressure by action of said pressure differential; an inlet port in said valve body communicating with said inlet, an outlet port, a passageway connecting said outlet port with the inner ends of said channels, a valve operable relative to said ports for regulating the pressure in parts of said valve body, and means for communicating the control pressure from said annular port to said regulating valve.

6. A valve of the character referred to, comprising a valve body having an inlet for fluid of variable pressure and an outlet for fluid of variable pressure, a differential plunger in said body responsive to the pressure differential between said inlet and outlet and in communication at the top and bottom thereof with said inlet, said plunger having means for co-operation with said body to provide variable length viscous flow passageways and being operable in one direction to regulate the rate of flow through said passageways and in another direction to vary the capacity of the valve, a stationary member extending through said plunger and provided with an annular port adapted to generate a variable control pressure by action of said pressure differential; an inlet port in said valve body communicating with said inlet, an outlet port, passageways connecting said outlet port with the inner ends of said means, a valve operable relative to said ports for regulating the pressure in said valve body, and passageways for communicating the control pressure from said annular port to said regulating valve, the outer ends of said means communicating with said outlet.

7. A valve of the character referred to, comprising a valve body having an inlet for fluid of variable pressure, and an outlet for fluid of variable pressure; a spring-loaded differential plunger in said body responsive to the pressure differential between said inlet and outlet and in communication at the top and bottom thereof with said inlet, said body and differential plunger provided with channels adapted for mutual engagement by the hydraulic actuation of said plunger to establish viscous flow passageways and regulate the length thereof, a stationary member extending through said plunger and forming spaced capillary seals therewith to generate a variable control pressure by action of said pressure differential, said member having an annular port, an inlet port communicating with said inlet, an outlet port, a passageway connecting said outlet port with the inner ends of said channels, a regulating valve operable relative to said inlet and outlet ports, and means for communicating pressure to both ends of said regulating valve; the outer ends of said channels communicating with said outlet.

8. A hydraulic slip compensating valve having an inlet for fluid of variable pressure and an outlet for fluid of

variable pressure and means responsive to the pressure differential between said inlet and outlet, said means comprising; a valve body, a channeled portion in a part of said valve body, and a chamber surrounding the intake end of said channeled portion; a spring-loaded differential plunger within said valve body and at opposite ends in communication with said inlet, said plunger having means for co-operation with the channeled portion in said valve body to provide viscous flow passageways and regulate the length thereof; an axially disposed member extending through said plunger, capillary seals in said plunger adapted to co-operate with said axial member to define an annular space in communication with said outlet, said axial member having an annular port for co-operation with one of said seals to generate a variable control pressure under the action of said pressure differential; an inlet port in communication with said inlet, an outlet port, a regulating valve operable relative to said ports, passageways for communicating the control pressure in said annular port to one end of said regulating valve, passageways connecting the other end of said regulating valve with said chamber, a passageway connecting said outlet port with said chamber, said variable length passageways terminating in an annular space, and means connecting said annular space with said outlet to communicate the outlet pressure thereto.

9. A slip compensating valve having an inlet for fluid of variable pressure and an outlet for fluid of variable pressure and means responsive to the pressure differential between said inlet and outlet, said means comprising: a valve body; a spring suspended differential plunger within said valve body and at opposite ends thereof in communication with said inlet; said body and said plunger provided with mutually cooperating means to provide viscous flow passageways; a chamber in communication with the intake end of said viscous flow passageways, said viscous flow passageways terminating in said outlet; an axially disposed member extending through said plunger, capillary seals defining an annular space between said plunger and said axial member, said annular space in communication with said outlet, said axial member having an annular port for co-operation with one of said seals to generate a control pressure under the action of said pressure differential, an inlet port communicating with said inlet, an outlet port communicating with said chamber, a regulating valve, means for conducting the control pressure from said annular port to one end of said regulating valve, and means for connecting said chamber with the other end of said valve for operating said regulating valve relative to said ports.

10. A slip compensating valve having an inlet for fluid of variable pressure and an outlet for fluid of variable pressure, said valve comprising a valve body; means defining serrated fluid metering capillary passageways within said valve body; means defining a variable control-pressure generating capillary passageway within said valve body; plunger means in said valve body and responsive to the pressure differential between said inlet and outlet for varying the lengths of said serrated fluid metering capillary passageways and the length of said variable control-pressure generating capillary passageway in unison and in direct proportion to said pressure differential; means converting the variations in length of said control-pressure passageway to non linear control-pressure values represented by the formula

$$P_c = PL \left(1 - \frac{PL}{PL \max.} \right)$$

70 wherein the control pressure is represented by P_c , the prevailing inlet pressure by PL and the maximum unit pressure for which the valve is designed by $PL \max.$; servo valve means responsive to the instantaneous control pressure for metering fluid to said serrated fluid metering

passageways at a rate adequate to maintain a pressure drop in said fluid metering passageways equal to the instantaneous control-pressure, whereby said servo valve means meter controlled quantities of fluid through the valve automatically at a rate inversely proportional to the pressure differential between said inlet and outlet; and means to vary the capacity of the valve.
